THERMAL CIRCUIT CLOSER

Filed Jan. 20, 1927

FIG. 2.

FIG. 3.

884

Inventor:
John M. Johnson,

Witness:

Dred C. Fisher.

F. G. Fisher,

Attorney.

UNITED STATES PATENT OFFICE.

JOHN M. JOHNSON, OF KANSAS CITY, MISSOURI.

THERMAL CIRCUIT CLOSER.

Application filed January 20, 1927. Serial No. 162,323.

My invention relates to a thermal circuit closer including a fuse which is adapted to be destroyed at a predetermined temperature for the purpose of releasing a spring contact 5 which closes an electric circuit including one or more suitable signals, and one object of the invention is to provide a simple and inexpensive device of this character in which the fuse can be easily renewed after being burned 10 out.

A further object is to provide a device of this character which can be examined and repaired without removing the device from any supporting means to which it may be applied.

15 While the device is capable of use in various situations, in the present instance I have shown it installed upon an internal combustion engine for the purpose of closing a signal circuit before said engine can become overheated to such an extent as to endanger its 20 bearings.

In order that the invention may be fully understood, reference will now be had to the accompanying drawing, in which:

25 Fig. 1 shows the device applied to an engine.

Fig. 2 is a central vertical section of the device with the contacts thereof held in inactive position by fusible metal.

30 Fig. 3 is a view similar to Fig. 2, excepting that the fusible metal has been burned out and released the contacts, one of which has sprung into engagement with the internal portion of a housing forming a part of the device.

Fig. 4 is a detail of a spring member and a 35 conductor for supporting said spring member.

Referring in detail to the different parts, 2 designates a tubular metallic housing having external threads 4 adjacent to one end and a circumferential shoulder 6 adjacent to said 40 threads. The end of the housing 2, adjacent to the screw threads 4, is closed by a thin disk 7 of copper or other suitable metal, while the opposite end of the housing 2 is closed by a bushing 8 made of insulating material and 45 threaded into said housing.

10 designates a binding post extending axially through the bushing 8 and into the housing 2. The binding post 10 is threaded into the bushing 8 and is further secured thereto by a lock-nut 12. The outer end of the binding post 10 is provided with a thumb nut 14 for securing one end of a wire conductor 16 against the lock-nut 12 and said binding post 10.

18 designates a metallic conductor arranged

within the housing 2 and threaded upon the inner end of the binding post 10.

20 designates a metallic spring member which, in the present instance, is folded midway between its ends and fixedly mounted at 60 its folded portion within the conductor 18. The free ends of the spring members 20 are bent in opposite directions to form contacts 22, one or both of which are adapted to engage the interior of the housing 2. Normally the 65 contacts 22 are held together and out of engagement with the housing 2 by fusible solder 24.

In order to install the device on an engine 70 it is only necessary to drill a small hole in the engine crank case or the oil pan and screw the threaded portion 4 of the housing 2 into said hole until the adjacent end of the shoulder 6 abuts the outer surface of said crank case or 75 pan. After the housing 2 has been installed 75 its inner end projects into and is exposed to the internal temperature of the engine and the composition of the fuse 24 is such that it will become destroyed before such temperature arises to a high enough degree to endanger 80 the crank shaft bearings.

As hereinbefore stated, the device may be used in various places and in connection with different kinds of circuits, but in the present instance I have shown it applied to the 85 lower portion of an automobile engine A and arranged in a circuit consisting of the wire conductor 16, a battery B, a suitable visual signal such as a lamp 26 and a suitable audible signal such as a horn 28. With the engine A thus equipped it is apparent that should its temperature rise above normal while in operation and before its crank shaft bearings become damaged from overheating, the fuse 24 will become destroyed thereby 95 releasing the spring member 20 so that its freed ends will spring apart and carry one or both of the contacts 22 into engagement with the interior of the housing 2, thus closing the circuit through the wire conductor 100 16, the battery B, the signal light 26, the horn 28, through ground to the engine A, the housing 2, the contact 22 and spring member 20, the conductor 18, the binding post 10 and back to the battery through the wire conductor 16, thereby notifying the driver of the car so that steps may be taken to correct the trouble which caused overheating of the engine. The disk 7 serves to prevent oil 105 from splashing into the housing 2 and also

110

prevents the melted fuse from running out into the engine.

After the fuse 24 has been destroyed as above stated, it is not necessary to remove the tubular housing 2 from the engine in order to renew the fuse as such renewal may be accomplished by merely removing the bushing 8, after which the conductor 18 can be unscrewed from the binding post 10 and another conductor substituted with a spring member 20 having its contacts held together by a fuse, it being understood that a supply of the conductors 18 with the springs 20 and fuses 24 may be carried under the seat of the motor vehicle ready for emergencies. The ends of the spring members 20 from which the fuses have been destroyed can again be secured together at any convenient time with other fusible solder so that the conductors 18 and the spring members 20 may be used repeatedly.

The battery B and the horn 28 may constitute the regular equipment of the automobile, in which the engine A is installed, while the lamp 26 is preferably arranged on the dash in front of the driver.

From the foregoing description it will be apparent that I have provided a thermal

circuit closer embodying the advantages above pointed out, and while I have shown and described the preferred construction and arrangement of the several parts I reserve all rights to such changes and modifications thereof as properly fall within the spirit and scope of the invention as claimed.

Having thus described my invention, what I claim and desire to secure by Letters Patent, is:

A thermostatic circuit closer consisting of a tubular conductor housing threaded at one end in order that it may be screwed into an engine, metallic means for closing said threaded end, a bushing closing the opposite end of said housing, a binding post extending into said housing through said bushing, a metallic conductor removably mounted upon the inner end of said binding post, a spring member folded at its intermediate portion and secured to said metallic conductor and having its ends bent in opposite directions to engage the inner surface of the housing, and fusible means for normally holding the ends of said spring member together and out of contact with the housing.

In testimony whereof I affix my signature.

JOHN M. JOHNSON.
